UNITED STATES PATENT OFFICE.

RUSSELL S. CARTER, OF NEW YORK, N. Y.

MOTOR-CAR BODY.

1,144,999.

Specification of Letters Patent.

Patented July 6, 1915.

Application filed June 3, 1910. Serial No. 564,755.

To all whom it may concern:

Be it known that I, RUSSELL S. CARTER, a citizen of the United States, residing in the borough of Manhattan, city, county, and State of New York, have invented the new and useful Improvements in Motor-Car Bodies described in the following specification, which is a full, true, and concise description of the said improvements, as required by statute.

The invention is an improvement in motor-car bodies built or adapted for use with roofs or tops of a collapsible or removable nature, and its object is to provide supplementary side closures to such roofed motor-car bodies which may be removed or erected at pleasure and which will afford a more effective and convenient protection against the weather than the flexible curtains or similar devices now commonly used.

The object of the invention is more particularly to provide a dismountable or removable window casing, adapted to be attached to the wall of the motor-car body to close the space between the same and the roof or top of the car and, more especially, to be attached to the top of the door of the motor car to form a structural extension thereof reaching to the roof, so that entrance and exit may be had independently of such other means as may be used to close in the remainder of body and without disturbing the same, the car body being thus provided with means by which it can be transformed from an open car body to a completely closed body, and in either condition presenting a neat and attractive appearance. These and other objects and advantages which will be apparent to those familiar with this art are attained by the embodiments of the invention hereinafter described as well as by the particular embodiment thereof which is taken for illustration in the accompanying drawings.

Referring to the latter, Figure 1 is a side elevation of a portion of a motor car body provided with a so-called cape-top of familiar design and using this invention; Fig. 2 is a vertical section through the door thereof, showing the window casing of this invention in place thereon; Fig. 3 is an enlarged top plan of the door and its joint member; Fig. 4 is a detail in vertical section of a modified form of separable joint,

later described; Fig. 5 is an enlarged detail of the joint in vertical section of Fig. 2 showing the window sash open; Fig. 6 is a similar view showing the casing replaced by a cap rail and also showing the latching device in its operated position; Fig. 7 is a vertical section of the joint between the door and window casing taken in the transverse plane of the lock or latching means and in the normal position of these parts; 65 and Fig. 8 is a longitudinal section through the latching means in the same condition.

The cape-top shown in Fig. 1 is formed of fabric impervious to water and is adapted to be supported in the position shown, by the usual bows and forward and rear stays 1, forming a continuous roof, which can be collapsed or removed in the well-known manner. A rear curtain 2 usually closes the space between the end of the roof and the rear body wall. The margins of the roof itself are brought down in a curve on either side forming the usual short valance 3, which terminates some distance above the side walls of the body, leaving an open space therebetween which is customarily closed in stormy weather by removable side curtains, the latter being buttoned onto the forward and rear stays in the obvious and familiar way. With other kinds of collapsible or removable roofs or tops, similar or equivalent means are correspondingly adapted to the roof supporting structure, to close in the open space referred to. The means contemplated by the present invention for this purpose is applicable with slight modification to any of the existing types of collapsible roofs or inclosures and consists of a removable side-closing section in the form of a window casing 4 which holds a transparent pane 5 and is adapted to be mounted by means of a separable joint upon the upper margin of the side wall of the body, so that it will meet or register with the roof or valance 3 in a satisfactory storm-proof manner. Preferably such window-casing is mounted on the hinged portion 6 of the side wall, constituting the door of the car, as illustrated, in which case it corresponds in width to the width of the top margin of the door, and is proportioned to swing freely as a part of the door itself, under the hanging edge of the valance 3, but without engagement with any rigid framing or door jamb as customarily employed for doors, though 100

105

110

such a jamb or jamb extension can be employed if desired. The casing may be made of any suitable material, and in one or several parts, as preferred, and the transparent pane may be permanently fastened therein or held in a sash such as indicated at 7, which is hinged in the casing after the manner of ordinary window sashes, so that the window can be opened by swinging the sash outwardly as in Fig. 5 of the drawings. An extension sash-holder suited for this style of window is shown at 8 in the same figure. When the casing is made of wood, the pieces forming the sill and lintel thereof are fastened to the stiles by usual mortise joints and are likewise joined by means of long bolts 9, contained in vertical holes in the interior of the stiles, so that all the members are thus bound together providing a rigid frame well adapted to withstand moisture as well as rough usage without distortion. The mounting of the casing upon the wall or door 6 in the rigid manner required for the purposes of this invention is produced by two interlocking joint members 10 and 11, one of which is formed on or fastened to the bottom of the sill of the window casing, while the other is correspondingly secured or formed on the upper margin or edge of the door, the engagement between the two being produced by sliding the one upon the other, longitudinally or in a direction parallel to the window sill and the plane of the engaging faces of the joint. The upper member 10 is fitted to the bottom of the sill so as to be flush with its inside and outside faces as shown in Figs. 2 and 5, and clamped thereon by means of screws in addition to the stile bolts 9 above referred to, the heads of which are countersunk in the underside of the member, so that it thus forms a rigid, structural part of the casing itself. The mating face of this member is provided with an undercut or dove-tailed groove extending its full length, while the complementary member 11 is formed with a corresponding undercut tongue adapted to fit and slide snugly therein. The tongue member of the joint, as shown in Fig. 3, is formed in two halves or sections, one at each end of the joint, both sections being fitted and securely fastened by screws 13 to the top of the door and in alignment with each other, so that in effect they constitute but a single joint member and they are herein so regarded. The arrangement of the member in separate sections provides ample rigidity for the mounting and at the same time leaves uncovered an interior space, within the body of the door intermediate of the inner and outer walls thereof and between the two tongue-sections which may thus be utilized as a receptacle. The undercut tongue of the lower joint member is slotted along longitudinal lines adjacent its lateral margins,

as shown at 12, so that a series of tapered-headed screws 14 arranged as shown can be used as wedges for expanding the marginal portions of the tongue to compensate for the wear of the latter and produce a close-fitting joint, firmly holding the casing as a rigid, structural extension of the door itself. The terminals of the joint member are each fashioned to conform with the marginal edges of the door proper, when mutually engaged, and when they are made of brass the arrangement gives to the door a neat and ornamental appearance concealing the separable nature of the casing.

The two members are automatically locked against separation by a detent means in the form of a spring latch 15 carried in a recess in the upper member 10, which drops or springs into a corresponding slot 16 in the lower member when the two members become fully engaged, the latch assuming the position indicated by Fig. 8, and preferably locking the members against movement in either direction. The latch slot 16 in the lower member is somewhat wider than necessary to accommodate the latch alone and is occupied also by a latch releasing device which is adapted to move into engagement with the nose of the latch and lift it out of the slot, when it is desired to unlock the joint. The releasing device is composed of a block 17^a of angular cross-section occupying a recess 18 formed in the under face of the joint member at one end thereof as shown in Fig. 8. A projection 17 on the block 17^a extends upward into the latch slot at one side of the latch, being appropriately beveled, as is also the latch, so as to have a wedging and lifting action thereon. The plunger 19 of a push button 22 is screwed or otherwise fastened to the releasing block as an operating member therefor, and a spring 21 thrusting against the inside of the push-button head tends to hold the block in the retracted position indicated in Fig. 7, wherein the latch is free to enter its latch slot when the joint members are brought into full engagement. The plunger 19 is mounted in a hole in the side of its joint member, and its inner end is contained within a horizontal bore 20 on the opposite side of the block, so that the latter is thus supported on the rigid transverse bearings of the plunger, which confine it to the recess, allowing it to move freely back and forth therein as desired. It will be understood that the detent means 15 could be arranged on the lower member and the releasing means on the upper member if desired, but the arrangement described is preferred and, for convenience of operation, the button is located to be operated from the inside of the door.

Combined with the foregoing dismountable window casing, the invention includes

also a protective covering for the joint member of the door or wall which will complete the finish of the latter when the window casing is not in place thereon. The covering 5 for this purpose is a cap rail, composed of a joint member 10 similar to that on the window sill, and preferably provided with an exterior surface trim 23 matching the adjacent parts of the body. Like the window 10 casing, it is adapted for sliding and interlocking engagement with the tongue member on the door (see Fig. 6), and has a latch 15 of the same construction and arrangement adapted to enter the latch slot 15 when brought into registry therewith 16 and to be ejected therefrom by pressing the button 22. The trim 23 preferably extends over the sides of the joint member with a bead or half-round curve to give a desired 20 rail effect and thereby conceal the removable nature of the appliance. By providing the latch releasing device in the lower joint member as stated above to be preferred, the comparatively thin cap-rail is required to 25 carry only the flat spring latch, while the several moving parts involved in the construction of the releasing device are permanently installed in the door to serve both the cap-rail and the window casing.

30 The separable joint shown in Fig. 4 is merely a reversal of the joint above described, the undercut groove being here shown on the lower member 24 and the tongue 25 on the upper member; otherwise 35 the construction and mode of operation is the same, the fact being plain that various forms of interlocking joints may be substituted for the one herein specifically described without departing from the invention.

40 The usual windowed side curtain 26 may be used to close in the space between the window casing and the rear curtain 2, being buttoned in place upon the top of the body wall and to the rear or hinge side of 45 the casing.

I claim:

1. The combination with the wall of a motor car body, of a removable part constituting a structural upward extension of 50 said wall, separable interlocking joint members between said part and wall supporting the former wholly on the latter and preventing movement of said part both upward and to either side, said part being removable and replaceable by sliding it lengthwise of 55 said joint, and a releasable device holding said part against movement lengthwise of the joint.

2. The combination of a motor car body 60 of the type having a collapsible or cape top, a portion of the wall of said body being hinged to constitute a door, a removable part supported wholly by the door and filling the space between the same and the roof, 65 separable interlocking joint members on the

upper edge of said door and the lower edge of said removable part, respectively, solidly supporting said part and preventing movement thereof both vertically and to either side, said part being removable and replaceable by sliding it lengthwise of said joint, and means for holding said part against such lengthwise movement when in place.

3. In a motor car body, the combination of 70 a door having one of the members of a separable interlocking joint mounted lengthwise on its upper edge, and a removable window casing wholly supported on said door, having the complementary member of said joint mounted lengthwise on its lower edge, said members being undercut and having close engagement so as to hold said casing solidly both against lateral and vertical movement.

4. In a motor car body, the combination 80 of a door having one of the members of a sliding interlocking joint fixed lengthwise of its upper edge, a removable upward extension supported wholly by said door, having the complementary member of said joint 85 fixed lengthwise of its lower edge, and a spring detent holding said members against relative longitudinal movement.

5. In a motor car body, the combination 90 of a door, a removable upward extension thereof, a separable interlocking joint having its members disposed along the meeting edges of said door and extension respectively and affording solid support for said extension on the door without other 95 support, said extension being removable and replaceable by sliding lengthwise of said joint, and means for preserving a snug fit between said members regardless of wear.

6. The combination with the wall of a 100 motor car body and a part supported wholly thereon and constituting an upward extension thereof, said wall and extension having sliding interlocking joint members fixed longitudinally on their meeting edges, an 105 automatic latch carried by one of the parts to engage the other and hold them against relative longitudinal movement, and means acting transversely of said movement to release the latch.

7. In a motor car body, the combination 110 of the door thereof, a removable upward extension supported wholly by the door, separable slidably interlocking joint members on the meeting portions of said parts 115 constituting the means for solidly supporting the extension on the door, an automatic latch on one of the parts, the other part having a recess to be engaged by said latch, and means operative in said recess to disengage the latch therefrom.

8. In a motor-car body, the combination 120 with a window casing having thereon one member of a separable joint, a cap-rail provided with a similar member, and a com- 125

plementary joint member on the wall of the said body adapted for removably supporting either of said parts.

9. In a motor car body, the combination with the door thereof having thereon one of the members of a separable joint, of a sash or frame and a cap-rail both provided with similar joint members complementary to the door member, and adapted for alternate attachment to said door to complete the finish thereof.

10. A motor car body having a removable roof or top and a portion of its body wall hinged to form a door, the horizontal top margin of said door having an interlocking formation, in combination with a window casing and a cap-rail both provided with a complementary interlocking formation and each adapted for assemblage with said door by sliding thereon lengthwise of the joint therebetween.

11. A motor-car body having a collapsible roof or top and provided with one of the members of a dove-tail joint on the horizontal margin of the wall thereof, in combination with a cap-rail and a window casing

each provided with a complementary joint member and externally fashioned to complete the finish of the wall of said body.

12. The combination with the wall of a 30 motor car body, a part adapted to form a structural upward extension thereof and a cap rail, said part and rail being each formed for attachment to the body wall by sliding longitudinally thereon, of a latch carried by said attachable members to engage a slot in the body wall and a latch releasing device mounted on the said wall. 35.

13. The combination with the wall of a 40 motor-car body, of a removable part constituting a structural upward extension thereof, interlocking joint members on said wall and part adapted to be received one within the other, and means for expanding 45 the inner member.

In testimony whereof, I have signed this specification in the presence of two witnesses.

RUSSELL S. CARTER.
